UNITED STATES PATENT OFFICE.

GEORGE W. BEARD, OF ANDERSON, INDIANA.

DESIGN FOR A SULKY-SLEIGH.

SPECIFICATION forming part of Design No. 34,220, dated March 12, 1901.

Application filed February 14, 1901. Serial No. 47,384. Term of patent 3½ years.

To all whom it may concern:

Be it known that I, GEORGE W. BEARD, a citizen of the United States, residing at Anderson, in the county of Madison and State of Indiana, have invented a certain new and useful Design for a Sulky-Sleigh; and I do declare the following to be a full, clear, and exact description of the invention, such as will enable others skilled in the art to which it appertains to make and use the same, reference being had to the accompanying drawing, and to the letters of reference marked thereon, which forms a part of this specification.

My invention relates to a certain new and useful design for a sulky-sleigh.

The design is fully illustrated in the accompanying drawing, which, with the letters of reference marked thereon, forms part of this application, and in which drawing I have shown a perspective view of a sulky-sleigh embodying my design.

The essential features of my design reside in the peculiar form of the body portion of the vehicle and in the peculiar design of the runners connected therewith.

It will be observed that the body portion of

the vehicle consists of a smooth and unornamented portion A, which forms the back and sides of the seat, the same being curved upon opposite sides in the arc of a circle, and in the box portion of the vehicle, which is connected with and depends from the forward ends of the seat portion A, the said box having flat and unornamented sides which depend from the forward ends of the portion A, the lower edges of these end portions of the box being curved upon substantially the arc of a circle, as shown.

The runners, which are connected at their ends to the front and rear portions of the body of the vehicle, are curved upon substantially the arc of a circle.

Having thus described my invention, what I claim to be new, and desire to secure by Letters Patent, is—

The design for a sulky-sleigh, substantially as shown and described.

In testimony whereof I affix my signature in presence of two witnesses.

GEO. W. BEARD.

Witnesses:

GEORGE MCKINSTRY,
CHARLES A. CLEVENGER.
